UNITED STATES PATENT OFFICE

HARRY HARRIS, OF LOS ANGELES, CALIFORNIA

CHAIR

Application filed October 27, 1928. Serial No. 315,363.

This invention relates to an article of furniture having a seat and pertains more particularly to a cushion unit upon which the occupant may repose. The present invention contemplates the incorporation in such a unit of spring supports or load carrying members, and it is especially adaptable for seats for chairs, davenports, and the like, and the word "chair" is hereinafter 10 used to broadly define such articles.

Articles of furniture known in the trade as overstuffed furniture have seats which are commonly so constructed that they are dependent for their buoyancy upon groups 15 of helical springs mounted in the chair base side by side and upon resilient cushions which may also have springs. The present common practice is to provide a frame having webs of fabric forming a bottom there- 20 in, and in some instances slats serving the same purpose. Upon the webs or slats are mounted a plurality of helical springs side by side and tied together laterally by twine or cord. The unit so formed is covered and 25 serves as a support for auxiliary cushions or like members. The construction is such that the depression of its springs cause a lateral pull on the adjacent springs resulting in strains and distortions which are det- 30 rimental in the functioning of the springs and in their ultimate effect upon the springs themselves. Another fault of such structure is that single springs will often bear substantially the entire weight of the 35 occupant and thus will be fully compressed so that they are no longer buoyant. Furthermore, there are spaces between adjacent springs having no support. There are also structural limitations as to the size of individual springs, which limitations do not 40 permit the best functioning of the springs. Numerous other faults of such structures will be apparent to those familiar with the art.

It is the primary object of this invention 45 to provide a cushion unit such that it will conform with a cushioning effect to the body of the one occupying it and accommodate itself to the direction of application and distribution of the weight of the occupant as

an entirety. It is another and more specific object of this invention to provide a cushion unit which has limiting means incorporated therein to maintain the seat in a position such as to retain the forward edge in position 55 under the knees of the occupant. It is a still further object of this invention to provide a unit which is demountable and interchangeable adapting it to use with various types of chairs and enabling replacement without requiring alterations.

These objects together with other objects and corresponding accomplishments are obtained by means of the embodiments of my invention illustrated in the accompanying 65 drawings, in which:—

Fig. 1 is a perspective view of a cushion unit, with a fragment broken away to better show the construction; Fig. 2 is a front elevation of a complete chair with my im- 70 proved unit installed therein; Fig. 3 is a transverse section from front to rear of the chair showing a fragment of the chair body and a portion of the unit in side elevation; and Fig. 4 is a fragmentary section as seen 75 on the line 4—4 of Fig. 3, parts being shown in elevation.

Referring with more particularity to Fig. 1, the invention is shown embodied in an overstuffed chair of conventional appear- 80 ance. This chair comprises a body A and a seat unit B. The body of the chair may be constructed in the usual manner having a base or supporting frame 5 forming a part thereof and provided with a recess 6 serv- 85 ing as a seat for the cushion unit.

The unit comprises a rectangular under- frame preferably formed of wood having a front bar 7 and a rear bar 8 joined at the sides by spaced bars 9^a and 10^a, there being 90 a pair of such bars at each side of the unit. Secured to the members of a pair of side bars at about the center thereof are hangers 11 which depend below the bars and are pref- 95 erably made of strap iron of suitable dimen- sions. Fastened to the bottom of each hanger is a wood block 12 secured thereto by bolts 13. Secured to each hanger is an elliptic spring comprising semi-elliptic members 14 and 15 bent inwardly at their 100

ends and secured together to form a reentrant portion. Supported upon the upper side of the springs and secured thereto is a rectangular seat frame 16 for supporting 5 the cushion seat. The cushion seat has a basket 17 of any suitable form, such as straps of iron. Helical springs 18 are arranged side by side, some resting in the basket and some at the marginal edge upon 10 the bars of the frame 16. The cushion seat may be constructed in a different manner and is not essential to the broad inventive idea except that it should be resilient so that it will conform to the shape of the occupant. In order to complete the upholstering, an apron covering 19 extends between 15 the frames.

The structure as described shows a cushion seat supported upon the elliptic springs and 20 so arranged that upon placing a load upon the unit, the elliptic springs will take the load as an entirety and will absorb shocks and accommodate itself to the shifting of the occupant. The basket construction allows 25 sufficient spring depth for the cushion seat and yet does not require a height which will make it uncomfortable. The cushion seat may rock forwardly and backwardly. However, a shifting of the front edge under the 30 knees of the occupant causes the chair to be uncomfortable. In order to limit the rocking movement at the front and to confine such movement to the rear, I have provided limiting members 20 of bar form which are dis- 35 posed in the front reentrant portion of each spring and bridges the members of a pair of side bars, as best shown in Figs. 3 and 4. The seat is thus arranged so that the elliptic springs are not interfered with as to their 40 resiliency at the front, but the cushion is restrained against rocking at the front edge.

What I claim is:—

1. In an article of the class described, the 45 combination of a base having a supporting frame, a unit demountably supported on said frame comprising an underframe corresponding to said supporting frame and having side bars, hangers mounted on said side bars intermediate their ends, elliptic springs 50 supported on said hangers, each spring having a reentrant forward end, limiting members disposed within the reentrant ends, a seat frame supported on said elliptic springs, a basket forming a part of said seat frame 55 telescopically disposed within the latter and forming a housing for spiral cushion springs.

2. In an article of the class described, the 60 combination of a base having a supporting frame, a unit demountably supported on said frame comprising an underframe corresponding to said supporting frame and having 65 pairs of spaced side bars, hangers mounted on and depending between the members of the pairs of side bars intermediate their ends, elliptic springs supported on said

70 hangers, each spring having a reentrant forward end, limiting bars spanning the members of the pairs of side bars and disposed within the reentrant ends of the springs to restrain rocking of said cushion frame at the forward end, a seat frame supported on said springs, a basket forming a part of said seat frame telescopically disposed within the latter and forming a housing for spiral cushion springs.

3. In an article of the class described, the combination of a base having a supporting frame, a unit demountably supported on said frame comprising an underframe corresponding to said supporting frame and having 80 pairs of spaced side bars, hangers mounted on and between the members of each pair of side bars, said hangers depending from said bars and secured thereto intermediate their ends, elliptic springs supported 85 on said hangers, each spring having a reentrant forward end, limiting bars spanning the members of the pairs of side bars and disposed within the reentrant ends of the springs to restrain rocking of said cushion 90 frame at the forward end.

4. A cushion unit comprising an underframe and having side bars, hangers mounted on and depending from said side bars intermediate their ends, elliptic springs supported 95 on said hangers, each spring having a reentrant forward end, limiting members disposed within the reentrant end, a seat frame supported on said elliptic springs, a basket forming a part of said unit telescopically disposed within said seat frame and forming a 100 housing for spiral cushion springs.

5. A cushion unit comprising an underframe having pairs of spaced side bars, hangers mounted on said side bars intermediate their ends, both hangers depending from the members of the pairs of side bars and between said members, elliptic springs supported on said hangers, each spring having a reentrant forward end, limiting bars 110 spanning the members of the pairs of side bars and disposed with the reentrant ends of the springs to restrain rocking of said frame at the forward end, a seat frame supported on said elliptic springs, and a basket forming a part of said unit telescopically disposed within said seat frame and forming a housing for spiral cushion springs.

6. A cushion unit comprising an underframe having side bars, hangers mounted on said side bars intermediate their ends, elliptic springs supported on said hangers, each spring having a reentrant forward end, limiting members disposed within the reentrant end and a seat frame supported on 125 said springs.

7. A cushion unit comprising an underframe having pairs of spaced side bars, hangers mounted on and depending from said side bars intermediate their ends, each 130

hanger being disposed between the members of a pair of guide bars, elliptic springs supported on said hangers, each spring having a reentrant forward end, limiting bars spanning the members of the pairs of side bars and disposed within the reentrant ends of the springs to restrain rocking of said cushion frame at the forward end, and a seat frame supported on said springs.

10 In witness that I claim the foregoing I have hereunto subscribed my name this 20th day of October, 1928.

HARRY HARRIS.
